VENDING MACHINE

Harold T. Probasco, Inglewood, Calif., assignor to
 Oak Manufacturing Company, Inc., Los Angeles, Calif., a corporation of California.

Application November 13, 1948, Serial No. 59,798

9 Claims. (Cl. 312—89)

1

This invention relates in general to vending machines, but particularly to a coin controlled machine for vending articles of merchandise in bulk, such as candy, salted nuts, chewing gum, etc., and a primary object is to provide a vending machine for such purpose which while embodying some of the conventional features of machines heretofore and now used also includes several new, novel, and desirable features which affords greater simplicity, facility, and certainty of operation, more perfect sanitation in the handling, storing, and dispensing of food products, more security against unauthorized use of the machine and consequent losses by theft of the dispensed products and a substantial economy of production and maintenance when compared with other machines for a similar purpose.

The objects of invention therefore include means for producing the following results:

Streamlining the appearance of the assembled unit by the omission of protruding parts or surfaces which are prone to be fouled with dirt and grime and are conducive to unsightliness and unsanitariness;

Employment of a carefully studied design of all of the sub-units and parts to an extent which will permit rapid assembly and disassembly thereof and ready access to the material container for cleaning and replenishment and to the operating mechanism for easy and rapid repair, adjustment, replacement and service;

Redesign of a well known type of coin operating unit which will be effective for dispensing a quantity of merchandise only upon the insertion of a predetermined coin and which will automatically reject slugs or imperfect coins and thereby prevent a dispensing operation when unauthorized or an attempt is made to defraud the machine;

The provision of a dispenser spout or chute embodying quickly detachable parts for cleaning from the exterior of the machine in order to maintain sanitary conditions, especially of the parts with which the food products come in contact;

And, otherwise to improve on accepted and used types of machines for increasing the economy and benefits of use and decreasing the requirements of service, repair, operation, and replacement.

Other and more detailed objects will appear as the description progresses.

In the annexed drawings there is shown a preferred form of vending machine embodying my improvements, in which:

Fig. 1 is a perspective view of the machine;

2

Fig. 2 is a sectional elevation on line 2—2 of Fig. 1;

Fig. 3 is a cross-sectional plan view on line 3—3 of Fig. 2;

Fig. 3a is a fragmentary view of a brush and mounting therefor associated with the dispensing unit;

Fig. 4 is a partial sectional elevation on line 4—4 of Fig. 3, and showing details of the dispensing mechanism;

Fig. 5 is a rear elevational view of the coin controlled dispensing mechanism as viewed in the direction of arrow 5 in Fig. 4;

Figs. 5a and 5b are, respectively, fragmentary sectional views on lines 5a—5a, and 5b—5b of Fig. 5;

Fig. 6 is a fragmentary view of the tensioning means in the plane of line 6—6 of Fig. 4;

Figs. 7 and 7a are similar sectional views of devices cooperating to latch the dispenser against operation when a slug or undersized coin is used in attempt to defraud the machine, Fig. 7 showing the device when permitting operation by a coin of appropriate size and value, and Fig. 7a showing the same as locking the mechanism against operation as when a slug or coin of wrong size and value is used;

Fig. 8 is a view of the coin control mechanism as viewed in a plane adjacent the plane of Fig. 6; and

Figs. 9 and 10 are, respectively, sectional plans on lines 9—9 and 10—10 of Fig. 2.

Briefly described a vending machine embodying my improvements includes a base A, a hollow body B, a bowl or container C (usually of glass or other transparent material), a container mounting C' and a top D, which are arranged one upon the other in succession and are detachably held together by means of a single stay rod E. Said rod is threaded into a boss 1 on the upper side of bottom 2 of base B and may be held tight as by means of a locknut 3, as shown in Fig. 2. The upper end of rod E is fixed to the cylinder of a lock F, the barrel of which is held in a depending boss 4 from the wall 5 of top D. Lock F may be operated by a key G so that members A, B, C, and D may be locked together to prevent access to the interior of body B and container C, at will, or when unlocked said members may be quickly and easily detached for any purpose.

Bottom 2 of base A is of concave cross section and provides a suitable coin receptacle and an annular flange 2a is extended above bottom 2 for telescopically receiving the skirt 6 of body B. The upper end portion of body B is formed with an

external annular seat 7 to receive and support an annular flange 8 of member C', and member C' is formed with an internal seat 9 for receiving and supporting the lower edge of container C and a suitable gasket 10. A plate 11 overlies the upper edge of container C and is connected with member C' as by means of rods 12, 12 having pivoted butterfly heads 13 fixed to their upper ends while their lower ends are threaded into an internal depending wall 14 of member C'. Plate 11 has a central opening through which boss 4 of top D extends.

Thus, when lock F is operated for detaching the several units of the assembly the top is first removed, then the container C and its mounting C', and finally body B from base A. If desired by turning rods 12 through manipulation of butterfly heads 13 member C may be removed from mounting C'.

Member C' bears a frusto-conical member 15 having a flange 16 seated with gasket 10 on seat 9 of member C' and open at its bottom immediately above a dispensing unit H which is rotatably mounted on rod E within wall 14 of member C', as shown in Figs. 2 and 3. The wall 14 of member C' in which member 15 and dispensing unit H are mounted has a closed bottom 18 on which unit H rests. Said unit is generally conventional in form and is subdivided into a plurality of pockets 19, 19 etc., of uniform size which are open at their tops for receiving charges of material from container C of measured quantities of the material to be dispensed at each operation as the unit H is rotated by means hereinafter described. Pockets 19 are separated by radial portions 19' preferably bearing adjustable sheet metal separators 20 which are in the form of flat webs with depending flanges 21. Webs 20 are arcuately slotted at 22 to adjustably receive screws 23 whereby the size and capacity of pockets 19 may be varied at will.

The bottom 18 of wall 14 has an orifice 24 and a depending flange 25 around which the upper end of a delivery chute 26 fits, said chute being extended downwardly and forwardly on a curve and integral with the front wall 27 of body B, as shown in Fig. 4. Preferably, the outlet 28 of the chute is closed by a detachable flap 29 which is hinged at opposite points 30, 30 on the wall 27 of the body, as in open notches, so that at times it may be readily removed.

The pockets 19 of dispenser H are movable into registration successively as the dispenser is actuated for dispensing measured quantities of material from container C through chute 26 for use. Dispenser H includes a sprocket or gear 31 which rotates on the vertical axis of rod E and is driven by a pinion 32 fixed to a horizontal shaft 33 journaled in a boss 34 on a plate 35 of body B. An operating handle 0 is suitably fixed to shaft 33 for rotating dispenser H through shaft 33 and pinion 32 under the control of a coin actuated mechanism generally indicated at M and which, also, is of generally conventional type but embodies certain details of structure and arrangement of parts of my invention.

Said coin controlled operating mechanism is detachably mounted as a unit on the front wall of body B on the escutcheon plate 35 in the following manner. An inner plate 36 of the same size as plate 35 is attached by means of screws 37 to plate 35 and also extend through spacers 38, and plates 35 and 36 are so arranged that the margins of opposite sides of plates 35 and 36 will project over the corresponding margins of por-

tions 38 to provide grooves 39 to slidably receive opposite edges 40 of an opening in body wall 27 which extends from the upper extremity of flap 29 to the upper edge of body B where the slot is open to permit the bodily insertion and removal of unit M. The edges 40 of said slot are tapered correspondingly to provide a greater width of slot at the top than at the bottom, so as to facilitate the insertion and removal of unit M and eliminate nicety of fitting when the machine is assembled and disassembled.

The inner side of plate 35 has a circular recess 41 concentric with the axis of shaft 33 for rotatably receiving a combined locking and unlocking disc 42 (Fig. 8) fixed to shaft 33. Said disc has a single coin receiving recess 43 open at the periphery of the disc, two groups of ratchet teeth 44 and 45—one on each side of recess 43—and an intermediate concentric dwell 46 between said groups of teeth. Normally disc 42 is held with the coin recess 43 in registration with a slot 47 in member C' and a continuing slot 47' in plate 35 so that a coin may be conveniently placed in operating position in recess 42 when the machine is at rest.

Disc 42 is urged to normally inoperative coin receiving position by a spring 48 which extends for a few convolutions around shaft 33 and has its inner end anchored at 48' to a washer 49 rotatably carried on shaft 33 and its outer end anchored to plate 36 by one of the screws 37 (Fig. 5). Said washer has a plurality of radial extensions 50 thereon which overlie corresponding inclined arcuate beads 51 formed on the inner side of plate 36 and are spaced apart so that when the extensions 50 abut the ends of beads 51 the operating member 0 and disc 42 will be stopped at coin receiving position. When disc 42, however, is turned in a given direction as in a dispensing operation, the extensions 50 will climb upon and traverse the inclined surfaces of the beads and thereby tension the spring 48 and raise washer 49 away from plate 36 and disengage the washer from a pin 56' on disc 42 which at times extends through a hole 56 in the washer. Thus, the spring 48 serves the dual purposes of tensioning the operating member 0 and disc 42 and of holding washer 49 in engagement with pin 56' at times.

Members 0 and 42 rotate in a counterclockwise direction as viewed in Fig. 8, the extent of which movement depends upon the presence or absence of a coin L in recess 43. If no coin is in said recess a slight forward movement of disc 42 will move the trailing edge of recess 43 into abutment with the free end of a pawl 52 which is pivoted at 53 in plate 38 and is urged into engagement with disc 42 by a spring 54 in a recess 55 of plate 38, and such a slight movement will not suffice to operate dispenser H.

If, however, a coin L is held on the disc it will engage and lift pawl 52 out of interference with the trailing edge of recess 43, thereby permitting a complete revolution of said members and a consequent movement of dispenser H to an extent which will effect registration of one of its pockets 19 with orifice 24 and evacuation of the contents of such pocket and delivery thereof through chute 26 to the operator.

In the event an undersize or improper coin or slug be inserted in slot 43 means is provided for detecting the same and preventing operation of the machine by their use. For example, if a coin of less diameter or value than that of a predetermined coin is placed in slot 43 the end of pawl

52 will drop sufficiently to engage the trailing edge of slot 43 and prevent further forward and effective rotation of the members 0 and 42.

If a thinner than normal coin is used a detector 60 is employed to stop effective rotation of said members. Said detector is pivotally mounted at 61 on lugs 62, 62 bent outwardly from plate 36 and tensioned by a spring 63 coiled around pintle 61 and having one end 64 bearing upon detector 60 and the other end 65 bearing against plate 36, all as shown in Figs. 7 and 7A. The free end of detector 60 has a foot 66 extended through an aperture 67 of plate 36 so that in an authorized rotation of disc 42 (Fig. 7) the foot 66 will ride upon the flat face of the disc but upon the attempted fraudulent operation by the use of an improper coin or slug L' (Fig. 7A) the foot 66 will fall into coin slot 43 and engage the trailing edge of the slot after but a slight operation and thereby prevent a complete and effective operation of the dispensing mechanism.

As shown in Figs. 5 and 5B, the coin L is carried in slot 43 until disc 42 has been rotated to an extent which will register slot 43 with a coin receiving outlet 68 formed on the plate 36 and having an inclined bottom 69 for guiding the coin downwardly so that it will fall into the concave receptacle a of base A (Fig. 2).

Referring to Figs. 3, 3A, and 5 it will be noted that there is disclosed a novel leveling means arranged above the dispenser H for preventing an overfilling of pockets 19. The means shown for such purpose is also generally conventional in form but embodies certain structural improvements which render the machine more easily assembled and freer from operating troubles than units formerly used. Said leveling unit includes a plurality of so-called brushes 70, 70 commonly mounted on a segmental plate 71 (Fig. 4), the outer edge of which lies diametrically over dispenser H and the outer marginal portion of which is held in seat 9 between member C' and container C.

Plate 71 is of thin metal, is readily yieldable and has a row of upwardly bent ears 72 (Fig. 3A) near its inner straight edge 73. Brushes 70 are formed as coiled springs and their upper extremities are detachably but securely fastened to plate 71 by spreading the upper and adjacent coils 74 and 75 apart sufficiently to force the brushes rearwardly under the plate until the upper coils snap into position behind ears 72 as shown in Fig. 3A. Thus, as dispenser H moves under the brushes the surplus material is displaced from the pockets 19 in succession and the dispenser will rotate freely without crushing or breaking the material or clogging of the dispensing mechanism. The flexibility of the brushes and the blunt surfaces thereof in lieu of flat, though yieldable, blade-like scrapers affords reasonable assurance that the dispensed product will not be impaired and the particular form of and means for mounting the brushes is novel, simple, and effective.

It may be understood that at no time in the absence of a proper coin in slot 43 of disc 42 can the disc be rotated forwardly to a point beyond the engagement of pawl 52 with the trailing edge of slot 43 and even with an improper coin or slug in slot 43 the rotation of disc 42 would be stopped by engagement of the foot 66 of detector 60 and the trailing edge of slot 43. In either event the washer 49 which is keyed to disc 42 by pin 56 would not have been moved rotatably and axially to an extent sufficient to disengage the washer

from pin 56. When the washer is disengaged from pin 56 the tension of spring 48 operates to retract the washer on its axis until one of its extensions 50 snaps into position against an end of one of the ridges 51 while the disc 42 continues forward rotation until slot 43 is moved into registration with slot 47' in plate 35 and pin 58' is simultaneously registered with hole 56' of the washer, whereupon the tension of spring 48 will seat the washer again on the pin in preparation for a subsequent operation.

Importance of the washer 49 in the hookup of the operating member with the dispenser would be at once noted inasmuch as its function is to apply the tension of the spring 48 to the operating member 0 and disc 42 in order to always return said elements to normal coin receiving position if, perchance, the operating member is turned without a coin in slot 43. After disc 42 has been rotated forwardly with a coin in its slot to a point beyond possible engagement with pawl 52 the washer which has been also rotated to a corresponding extent will have at such point of engagement been disengaged from its pin 56' thereby rendering spring 48 effective for retracting the washer to normal position while the rotation of the disc continues to the extent of a full revolution. Thus the washer is releasably connected with the disc for the purpose of retracting the disc up to a given point in its rotation and thereafter permitting the continued free rotation of the disc to the end of a single revolution.

It is important also that the operating assembly include the plurality of inclined arcuate beads 35 or ridges 51 and that the washer includes a corresponding number of extensions 50 thereon alternating with an individually engaging said beads so that, as the washer is forwardly rotated, it is urged away from plate 36 axially and all of the extensions 50 are at all times in the same plane transversely of the washer axis instead of as in other machines for the same purpose tilting a member such as the washer 49 for accomplishing a similar result.

45 The essence of this invention accordingly is in the specific structural improvements embodied in the operating mechanism, the dispensing mechanism, and in the general assembly of the body sections A, B, C, C', and D which is superposed 50 one upon the other in succession, are commonly held in assembled position against unauthorized access by the single rod E and lock F, thereby permitting quick assembly and disassembly, and yet affording ample safety and security against 55 manipulation for the purpose of defrauding the machine or robbing it of its contents or the money accumulated in the base A.

I claim:

1. A vending machine comprising: a base, a 60 first body member mounted on said base, a second body member superposed on the second body member, a receptacle for dispensable material superposed on the second body member and provided at its bottom with a rotatable dispensing 65 unit and at its top with a cover, means for securing the second body member, the receptacle and the cover together for removal as a unit from the first body member and together with said dispensing member, means for securing said 70 receptacle and dispensing unit to said first body member and said base against unauthorized detachment, and an operating mechanism mounted on the first body member and operatively connected with said dispensing member.
2. A vending machine as characterized in 75

claim 1 in which a wall of said first body member is formed with a recess open at its upper edge for removably receiving said operating mechanism, whereby when the receptacle and associated elements are removed from the first body member the operating mechanism may be inserted or removed as a unit but not otherwise.

3. A vending machine as characterized in claim 1 in which a wall of said first body member is formed with a recess open at its upper edge for removably receiving said operating mechanism, whereby when the receptacle and associated elements are removed from the first body member the operating mechanism may be inserted or removed as a unit but not otherwise, said first body member having a delivery chute inwardly thereof for receiving material from the dispensing member and an outlet in a wall of the first body member for delivering dispensed quantities of material to a user.

4. A vending machine as characterized in claim 1 in which a wall of said first body member is formed with a recess open at its upper edge for removably receiving said operating mechanism, whereby when the receptacle and associated elements are removed from the first body member the operating mechanism may be inserted or removed as a unit but not otherwise, said first body member having a delivery chute inwardly thereof for receiving material from the dispensing member and an outlet in a wall of the first body member for delivering dispensed quantities of material to a user, said outlet being open at the bottom of the recess in which the operating unit is held, and a cover removably and hingedly seated at the top of and for normally closing said outlet, said cover being held in position by and removable from its seat only when said operating unit is removed.

5. A vending machine as characterized in claim 1 in which said last mentioned securing means includes a vertically disposed rod fixed at its lower end to the base and extended through the first and second body members, the dispensing unit and the receptacle and detachably secured to said receptacle cover.

6. A vending machine as characterized in claim 1 in which said last mentioned securing means includes a vertically disposed rod fixed at its lower end to the base and extended through the first and second body members, the dispensing unit and the receptacle and detachably secured to said receptacle cover, and a key operated lock

borne by the receptacle cover and operatively connected with said rod for separating said units without individual disassembly.

7. A vending machine as characterized in claim 5 in which said dispensing unit includes a plural pocketed member rotatable in each dispensing operation to an extent necessary to move a predetermined single charge of material to a position for delivery to a user.

8. A vending machine as characterized in claim 1 in which said dispensing unit includes a plural pocketed member rotatable in each dispensing operation to an extent necessary to move a predetermined single charge of material to a position for delivery to a user, and said operating unit includes a rotatable member, said rotatable operating member and said rotatable dispensing member having gears constantly engaged for effecting successive operations.

20 9. A vending machine as characterized in claim 1 in which said dispensing unit includes a plural pocketed member rotatable in each dispensing operation to an extent necessary to move a predetermined single charge of material to a position for delivery to a user, and said operating 25 unit includes a rotatable member, said rotatable operating member and said rotatable dispensing member having gears constantly engaged for effecting successive operations, the bottom of said 30 receptacle being partly open for communication with the pockets of the dispensing member, and yieldable elements depending from the closed portion of the receptacle bottom overlying the dispensing member for engagement with and directing the movement of material into the open 35 pockets of the dispensing member.
